UNITED STATES PATENT OFFICE.

SADIE C. WINFREY, OF DAYTON, TEXAS.

BAILER FOR WELLS.

Application filed May 22, 1925. Serial No. 32,141.

To all whom it may concern:

Be it known that I, SADIE C. WINFREY, a citizen of the United States, residing at Dayton, in the county of Liberty and State 5 of Texas, have invented certain new and useful Improvements in a Bailer for Wells, of which the following is a specification.

This invention relates to the new and useful improvements in a bailer for wells.

10 One object of the invention is to provide a device of the character designed for the purpose of bailing water, slush, and the like, from oil and other wells.

15 Another object of the invention is to provide a bailer which will automatically release part of its load in case it should become overloaded, particularly when being used as a swab.

20 A further feature of the invention is to provide a bailer which is capable of adjustment so as to vary its capacity for lifting loads. A still further feature of the invention is to provide a bailer that may be used as a swab.

25 With the above and other objects in view this invention has particular relation to certain novel features of construction, operation and arrangement of parts an example of which is given in this specification and illustrated in the accompanying drawings 30 wherein:—

Figure 1 is a fragmentary vertical sectional view of the bailer and Figure 2 is a side view thereof.

35 In the drawing the numeral 1 designates the barrel of the bailer which is tubular in form. Connected to the lower end of this barrel, by the coupling 2 there is a relatively short tubular housing 3, whose lower end is 40 formed with an internal annular web 3', having a relatively large central opening 4. Threaded through this web are the adjusting bolts 5, 5, resting on the upper ends of which there is the annular plate 6 having a 45 relatively large central opening 7.

Clamped between the adjacent ends of the barrel and the housing there is an annular plate 8 having the upwardly flared central opening 9, forming a valve seat, and also having the drain ports 10, 10. There is a disc valve 11, having a relatively large central opening 12, said disc being seated on a coil spring 13 which rests on the plate 6 and is confined in the housing 3 and normally holds the valve against the underside of the plate 8 and closes said drain ports.

There is an upwardly opening valve 14, conforming to the shape of, and adapted to seat in, the valve seat 9. Attached to this valve there is a stem which depends through the openings 12, 7 and 4, and whose lower end has a cross pin, normally spaced beneath the web 3', and adapted to engage against said web to limit the upward movement of the valve.

There is a short tubular section attached to and depending from the lower end of the housing 3 and provided to protect the valve stem and the set screws 5 against injury, and surrounding the housing there is, in some cases, the swab 17, sleeve like in form and composed of rubber or other suitable materials, and which fits closely within the screen 18.

75 The bailer is first let down into the well bore and withdrawn therefrom, by the conventional bailing line 19. As the bailer passes downwardly through the fluid, said fluid passes up through the openings 4, 7, and 12 and lifts the valve 14 and passes into the barrel. When the bailer is pulled upwardly the valve 14 seats and the fluid is thereby retained in the bailer barrel and withdrawn to the ground surface. In case the barrel receives an overflow of fluid, the spring 13 will yield, permitting the valve 11 to open the ports 10 and the excess load will be drained out and there will, thus, be no danger of breaking the line. This excess load is most likely to occur, when the swab 17 is in use, as this swab fits snugly in the screen and is designed to clean the screen out preparatory to bringing in the well.

80 The compression of the spring 13 may be varied, through the adjusting screws 5, and the capacity of the bailer thus varied so as to accommodate the line to the load it is capable of carrying.

85 What I claim is:—

1. A bailer including a barrel, an upwardly opening valve in the bottom thereof, a downwardly opening valve at the bottom of the barrel, a yieldable member normally holding said last named valve closed.

105 2. A bailer including a barrel, an upwardly opening valve in the bottom thereof, a downwardly opening valve at the bottom of the barrel, a yieldable member normally holding said last named valve closed, and means for varying the compression of said yieldable member.

110 3. A bailer including a barrel, an upward-

- ly opening valve, and a downwardly opening valve arranged at the bottom thereof, and a yieldable member normally holding said last named valve closed.
5. A bailer including a barrel having a lower end plate provided with ports, an upwardly opening valve normally closing one of said ports, a downwardly opening valve normally closing the other of said ports, a 10 yieldable member normally holding said last mentioned valve closed, and means for varying the influence of said yieldable member on said valve.
5. A bailer for wells including a barrel 15 whose lower end is provided with a valve seat and a drain port, a housing carried by the lower end of the barrel, an upwardly opening valve adapted to co-operate with said seat, a downwardly opening valve in 20 said housing, a yieldable member in the housing sustaining said downwardly opening valve and normally holding it in position to close said port.
6. A bailer for wells including a barrel 25 whose lower end is provided with a valve seat and a drain port, a housing carried by the lower end of the barrel, an upwardly opening valve adapted to co-operate with said seat, a downwardly opening valve in 30 said housing, a yieldable member in the housing sustaining said downwardly open-
- ing valve and normally holding it in position to close said port, and means for varying the influence of the yieldable member on said downwardly opening valve. 35
7. A bailer for wells including a barrel whose lower end is provided with a valve seat and a drain port, a housing carried by the lower end of the barrel, an upwardly 40 opening valve adapted to co-operate with said seat, a downwardly opening valve in said housing, a yieldable member in the housing sustaining said downwardly opening valve and normally holding it in position to close said port, and a sleeve-like swab 45 around said housing.
8. A bailer for wells including a barrel whose lower end is provided with a valve seat and a drain port, a housing carried by the lower end of the barrel, an upwardly 50 opening valve adapted to co-operate with said seat, a downwardly opening valve in said housing, a yieldable member in the housing sustaining said downwardly opening valve and normally holding it in position to close said port, a sleeve-like swab 55 around said housing and means for varying the influence of said yieldable member on said last named valve.

In testimony whereof I have signed my 60 name to this specification.

SADIE C. WINFREY.
